(57) **CLAIM**

The ornamental design for a splice enclosure bracket, as shown and described.

DESCRIPTION

FIG. 1 is a perspective view of a splice enclosure bracket according to one embodiment.

FIG. 2 is a left-side view of the splice enclosure bracket in FIG. 1, where the right-side view is a mirror image thereof, and therefore not shown.

FIG. 3 is a front view of the splice enclosure bracket in FIG. 1.

FIG. 4 is a back view of the splice enclosure bracket in FIG. 1.

FIG. 5 is a top view of the splice enclosure bracket in FIG. 1.

FIG. 6 is a bottom view of the splice enclosure bracket in FIG. 1.

FIG. 7 is a perspective view of a splice enclosure bracket according to another embodiment.

FIG. 8 is a left-side view of the splice enclosure bracket in FIG. 7, where the right-side view is a mirror image, thereof, and therefore not shown.

FIG. 9 is a front view of the splice enclosure bracket in FIG. 7.

FIG. 10 is a back view of the splice enclosure bracket in FIG. 7.

FIG. 11 is a top view of the splice enclosure bracket in FIG. 7; and,

FIG. 12 is a bottom view of the splice enclosure bracket in FIG. 7.

The broken lines in the drawing depict portions of the splice enclosure bracket that form no part of the claimed design.
